UNITED STATES PATENT OFFICE.

BEVERLY L. WATERS, OF AURORA, ILLINOIS.

SHELVING.

971,707.

Specification of Letters Patent.

Patented Oct. 4, 1910.

Application filed April 27, 1908. Serial No. 429,490.

To all whom it may concern:

Be it known that I, BEVERLY L. WATERS, a citizen of the United States, residing at Aurora, in the county of Kane and State of Illinois, have invented a certain new and useful Improvement in Shelving, of which the following is a specification.

My invention relates to metallic shelving and its objects are, first, to provide a construction such that the shelving may be built in sections and assembled in a space too small to admit of the use of long connecting or tie rods extending over two or more sections; second, to provide jointed tie rods so constructed that a single joint or section is sufficient for each interior section of the shelving; third, to provide shelving in which the shelves are under compressive and the tie rods under tensional strain; fourth, to provide a structure in which the shelves, which are under compression, longitudinally, act as braces and stiffeners for the entire structure.

I accomplish these objects by the construction shown in the accompanying drawings, in which:

Figure 1 is a general view of shelving embodying my invention. Fig. 2 is a transverse sectional elevation thereof. Fig. 3 is a bottom view taken on the line 3—3 Fig. 2. Fig. 4 is a fragmentary sectional view taken upon a vertical plane passing through the center of the tie rods at the joining ends thereof. Fig. 5 shows the preferred manner of securing the ends of the rods to the end partition. Fig. 6 is a longitudinal sectional view of a tie rod. Fig. 7 is a sectional elevation of a few sections of shelving. Fig. 8 is a perspective view showing the construction of the shelf at the end thereof. Fig. 9 is a longitudinal sectional view of a tie rod in an alternative form, solid instead of hollow.

Similar numerals refer to similar parts throughout the several views.

The structure in general consists of upright partitions 10, tie rods 11 and shelves 12. The drawings show said partitions stiffened by means of upright strips 13.

The tie rods which coöperate with the shelves to hold the structure in shape embody one of the elements of the present invention and consist of either solid or hollow rods threaded internally at one end and externally at the other. The preferred rod

is hollow, as shown for example in Fig. 6 and consists of metal tubing "upset" at one end so as to be thick enough to be internally threaded as at 14. The opposite end is also upset or forged so as to produce a portion 15 of reduced diameter which is externally threaded so as to fit in the internal threaded portion 14 of the next tie rod. As portion 15 is reduced in diameter there is formed a shoulder 16 between the reduced threaded portion and the body of the rod as best shown in Fig. 6. It will be noted that with this formation at the ends of the rods, two rods when screwed together present a uniform external surface there being no protuberance or unevenness which might prevent the shelf from setting down flat along the entire length of the rod.

When the parts are to be screwed up in tightening the structure an ordinary pipe wrench may be employed, although in certain instances I form two flat surfaces 17 upon the rod to receive an ordinary spanner wrench.

The partitions 10 are apertured to just receive the reduced portions 15 of the tie rods and permit said reduced portions to be freely inserted and withdrawn.

The shelves 12 consist of sheet metal and have flanges 18 formed at their front and rear edges for stiffening the shelf and assisting to prevent frontward or rearward shifting. This will be understood by reference to Fig. 2 of the drawings. At the ends of the shelf are formed depending flanges 19 which are adapted to bear against the partitions 10 and thus brace the structure when the tie rods are screwed up tight.

When the structure is to be erected, the partitions are placed upright with the shelves between them and the rods are inserted within the reduced portion 15 at one end projecting through the aperture in one of said partitions as shown. The internal threaded portion 14 of the rod of the adjoining section is then screwed onto it and tightened up after the shelf of the next section has been put in place. The parts are so proportioned that the shelves are longer than the distance between shoulder 16 and the far end of the rod, and hence when the rods are tightened up the shelves come to a bearing against the partitions before the rods do; consequently the shelves are under compression while the rods are under tension,

and by screwing the rods up tightly the bracing action of the flanges 19 becomes very effective and holds the structure firmly in shape.

5 It is clear from the drawings and above description that the entire structure is composed, practically speaking, of only three kinds of members, to wit, the partitions, the shelves and the tie rods. No couplings, nuts 10 or bolts are required, with the exception of the ones at the very ends of the structure. It is also clear that the entire structure is tightened by merely rotating the tie rods themselves; moreover the rods are practically 15 speaking no longer than the shelves, and a large space is not required for assembling as would be the case if a single tie rod extended through from one end of the shelving to the other. Hence my shelving is not 20 only simple in construction and extremely rigid, but may be readily put up in vaults, closets or store rooms where the space for assembling is necessarily limited.

Having thus described my invention, what 25 I claim as new, and desire to secure by Letters Patent, is:

1. In shelving, the combination of a set of upright partitions, a set of shelves located between each two partitions and tie rods for 30 holding the same together, each tie rod having an internally threaded portion at one end and an externally threaded portion at the other, the externally threaded portion being of reduced diameter and forming a 35 shoulder adapted to abut the partition, and the partitions being apertured to permit the reduced portion of the rod to project through from one side to the other, and said rods, measured from one end to the shoulder

at the opposite end, being less than the 40 length of the shelf.

2. In sectional shelving, the combination of upright partitions having apertures therein, shelves having flanges at the ends adapted to bear against the sides of the partitions 45 and rods for supporting the shelves and drawing the partitions tightly against them, said rods having reduced portions at one end adapted to penetrate the apertures in said partitions to reach and screw into the internally threaded end of the next adjacent rod, the reduced portion forming a shoulder on the rod, and the shelves being longer than the tie rods measured from one end to the shoulder at the other end, whereby the tightening 50 of the rods holds the partitions tight against the ends of the shelves and thereby 55 rigidifies the structure.

3. In sectional shelving, the combination of shelves having vertical flanges at the ends, 60 upright partitions having apertures therein, and tie rods of uniform cross sectional outline except at one end where each rod is reduced thereby forming a shoulder, the reduced portion of said rod being threaded 65 and the opposite end internally threaded whereby one rod may screw into another on the opposite side of a partition, and the shelves being longer than the rods measured from one end to the shoulder on the opposite 70 end.

In witness whereof, I have hereunto subscribed my name in the presence of two witnesses.

BEVERLY L. WATERS.
